UNITED STATES PATENT OFFICE

2,233,488

BOX CONSTRUCTION

John N. Powell, Princeton, Ill.

Application May 13, 1938, Serial No. 207,649

2 Claims. (Cl. 229—7)

This invention relates to improvements in containers and more particularly to dispensing cartons for dry materials of a granular, comminuted or powdery nature, as for instance sugar, coffee, grains, cereals, soap flakes, chips, powders, and the like.

The main objects of the invention are to provide such a device with an operable closure and dispensing member so formed and incorporated 10 as to serve either as a plain closure or as a pouring spout which is readily swingable to accommodate one function or the other; to provide therefor automatic locking means for positively retaining the spout member in its outlet closing 15 position; to provide for making such a container from a single blank of flat stock material; to provide therein movement limiting side wings for the pouring spout; to provide in such a device, means to prevent the pouring spout from 20 being forced inward too far or into the interior of the container; to provide in such a device, guide means to keep the side wing travel close to the adjacent side walls respectively; and to provide a device of this character which is simple 25 in construction and operation, and inexpensive to manufacture.

Other objects and advantages of this invention and its great utility will be apparent from the accompanying drawings and description.

30 Three illustrative embodiments of the present invention are shown in the accompanying drawings in which:

Figure 1 is a perspective view of my improved container in closed or inoperative position.

35 Fig. 2 is similar to Fig. 1 except it shows the tongue-bearing stationary flap partly pressed inwardly in the direction of the arrow.

Fig. 3 is a fragmental perspective view of the same showing the pouring spout in open or operative position.

40 Fig. 4 is similar to Fig. 2, except the pouring flap is shown pressed inwardly beyond the normal closed position to cause the tongue lock to be seated on the outer face of the pouring flap and positively lock the same in closed position.

Fig. 5 is a fragmental sectional view taken on the line 5—5 of Fig. 4.

Fig. 6 is a view showing the blank from which the container is made.

45 Figs. 7 and 8 are perspective views of a modified form of container showing the same in closed position in Fig. 7 and in open position in Fig. 8.

Fig. 9 is a fragmental sectional view taken on the line 9—9 of Fig. 7.

Fig. 10 is a view showing the blank from which the container shown in Figs. 7 to 9 is made.

Figs. 11 and 12 are perspective views of another modified form of container shown in closed position in Fig. 11 and in open position in Fig. 5 12.

Figs. 13 and 14 are sectional views taken on the lines 13—13 and 14—14 of Fig. 11, respectively.

Fig. 15 is a view showing the blank from which 10 the container shown in Figs. 11 and 12 is made.

The novel containers disclosed are formed from single blanks of single sheet material such as cardboard, fiber board, and like materials.

In the embodiment shown in Figs. 1 to 6, the pasteboard container 1 is made from a blank 2. It is provided with side wall panels 1' and 1'' and end wall panels 3 and 4, the longitudinal edges of which are defined by suitable score lines 20 5, 6, 7 and 8 to facilitate folding. The bottom of the container is composed of flaps 9, 10, 11 and 12 folded one over the other as is customary in containers of this general class.

The top construction, wherein resides the 25 present invention, comprises pairs of side and end flaps 13, 14, 15 and 16. Score lines 17 and 18 extend the full length of the blank and define the tops and bottoms of the vertical walls of the container.

30 The pouring spout comprises the end flap 15 and side wings 19 and 20. The side flaps 14 and 16 and wings 19 and 20 are so cut that the flaps 14 and 16 are provided with integrally formed projections or limit stops 21 and 22 and the 35 wings 19 and 20 with retaining projections or stops 23 and 24, the mutually related stop purpose of which will be hereinafter described.

The side flap 16 is also formed with a resiliently yieldable tongue 25 to serve as a locking 40 means for the dispenser spout when the dispenser is in closed or inoperative position.

In folding the blank 2 to form the container 1, it is first folded along the score lines 5, 6, 7 and 8 to the position substantially as shown 45 in Figs. 1 to 4 after which the elongated narrow gummed strip 26, shown attached integrally to end panel 3 at the score line 5, is fastened to the inner side of the side wall 2 in the usual manner. The top flap 13 is then folded inwardly 50 and flap 14 folded thereon; then the flap 16 is folded on the flap 14 and is secured thereto by gluing, cementing or the like. The wings 19 and 20 are then each bent inwardly toward each other and moved forwardly toward the interior 55

of the container and then each is forced outwardly, the wing 20 over the portion 22 and the wing 19 over the portion 21, so that each of the wings 19 and 20 will lie in the crotches 21 and 5 28 respectively formed on the flaps 14 and 16 respectively.

Figure 3 illustrates the position of the top after folding the container as described. It will now be noted that by turning the flap 16 forwardly to its most natural forward position, substantially as shown in Fig. 4, in closing the box, the edge 29 will abut against the protruding stops 21, 22 and tongue 25. Then by exerting a slight inward pressure at the point of and in 15 the direction of the arrow, shown in Fig. 4, the adjacent parts of flaps 15 and 16 will be bowed inwardly, and the flap 15 will also cause the tongue 25 to be bent inwardly about 45° or more, Fig. 5, and until the medial portion of the flap 20 15 is forced inwardly beyond length of the tongue, when the tongue 25 will straighten out and lie on the upper face of the flap 15, Fig. 1, thereby locking the pouring spout and completely closing the container. The protruding 25 portions 21 and 22 serve as side edge supports to prevent the flap 15 from being forced into the interior of the container.

To open the pouring spout, the stationary or non-folding flap 16 is pressed inwardly in the 30 direction of the arrow shown in Fig. 2. This also will bow the flaps 15 and 16 inwardly and will cause the tongue 25 to be bent outwardly in a direction substantially 90° or more from the position shown in Fig. 5. The flap 16 being 35 supported at its sides is thus bowed inwardly a sufficient distance to permit the tongue 25 to right itself under the flap 15. When the resilient spout flap 15 is thus released, it "snaps" outward to partially opened position. The flap 40 15 is then manually swung outwardly until the protruding portions or stops 23 and 24 abut against the portions 21 and 22 to limit the outward movement of the spout. It is now apparent how the flap 15 and wings 19 and 20 provide 45 a most convenient pouring spout and lid of unitary design. It is also to be noted that as arcuate edges of the wings 19 and 20 travel in the crotch portions 21 and 28 the wings are forced to travel in a plane parallel to the plane of the 50 side panels 1 and 2 and each adjacent thereto respectively.

The pourable dry material to be housed in the container is first inserted in the container upside-down, as by the packer, and then the flaps 55 9, 10, 11 and 12 are folded into closing relation to provide the bottom of the container.

In the two modified forms of construction shown in Figs. 7 to 10 and 11 to 14 the main body and bottom portions are identical to those 60 shown in the preferred embodiment of Figs. 1 to 6 and therefore like numerals are used to identify similar parts.

The modification of the construction shown in Figs. 7 to 10 resides in the top flaps. The flaps 65 13, 14 and 16 are the same as in the preferred embodiment except that the flaps 14 and 16 do not have the protruding portions 21 and 22. The pouring spout in this modification comprises a flap 15 having segmental wall portions 70 30 and 31 each of which is provided with an inclined score line 32 and score lines 33 and 34 extending from the vertical score lines 7 and 8 respectively to the top of the segmental portions 30 and 31.

75 It can readily be seen that when the segmental

portions 30 and 31 are creased on the score lines 32 and folded toward each other the flap 15 will tend to shift toward the container body. Slight pressure exerted on the flap 15 in the direction of the arrow A and substantially at that location 5 will cause the flap to bend the tongue 25 at right angles in the same manner as described in the preferred embodiment and lock the spout in closed position. Similarly as in the preferred embodiment slight inward pressure exerted at 10 and in the direction of the arrow B will cause the spout to snap open ready for a pouring operation.

Similarly as in the modified form shown in Figures 7 to 10, the body and bottom portions 15 of the modified form shown in Figs. 11 to 14 inclusive are similar to the forms shown in the preferred embodiment.

The top portion comprising flaps 13, 14, 15 and 16 are also similar except that the flaps 14 20 and 16 are provided with integrally formed longitudinally extending segmental strips 35 and 36 which are also formed integrally with the side panels 1' and 1'' respectively. See Figs. 12, 14 and 15. The flap 15 in this modified form is 25 not provided with side wings. It is apparent that the strips 35 and 36 serve to prevent the flap 15 from being forced into the interior of the carton.

The operation of this modified form is like that 30 of the previously described other forms.

Summarizing briefly, the tongue portion 25 acts as a locking means for the spout when not in use to prevent spilling of the contents and also to keep foreign matter out of the container. 35

The protrusions 21 and 22 and 35 and 36 serve to prevent the spout from being unduly forced into the interior of the container.

The protrusions 21 and 22 also serve as guide means for sliding wings 19 and 20 respectively 40 so as to limit the movement of the wings to nearly the same plane as the side panels 1' and 1'' and thereby prevent their interference with the contents of the container.

The entire carton may readily be stamped out 45 of a blank of cardboard or like material either with or without the aid of special tools or dies; and all the parts of the container are autogenously integral in the blank.

It is to be understood that some of the details 50 set forth may be altered or omitted without departing from the spirit of the invention as defined by the appended claims.

I claim:

1. A pasteboard box comprising a shell having an opening in one end thereof, a flap fixedly positioned across and closing substantially one-half of said end and having its free edge terminating substantially on a line transverse of said end of said box midway thereacross, a closure for 60 the remainder of said end comprising a flap hinged on one edge of said box opposite the free edge of the secured flap, the free edge terminating in substantial meeting relation with the free edge of said fixed flap, an integrally formed outwardly projecting tab positioned on the free edge of said fixed flap substantially in mid portion and overlapping said free edge of said closure flap, the resiliency of said closure flap and fixed flap and tab functioning to lock said closure flap in position by pressure thereon to snap said closure beneath said projecting tab and to release said closure from locking position from said tab by pressure on said fixed flap. 65
2. A pasteboard box comprising a shell having 70

ing an opening in one end thereof, a flap fixedly positioned across and closing substantially one-half of said end and having its free edge terminating substantially on a line transverse of said 5 end of said box midway thereacross, a closure for the remainder of said end comprising a flap hinged on one edge of said box opposite the free edge of the secured flap, the free edge terminating in substantial meeting relation with the free 10 edge of said fixed flap, an integrally formed outwardly projecting tab positioned on the free edge of said fixed flap substantially in mid portion and overlapping said free edge of said closure flap, the resiliency of said closure flap and fixed flap and tab functioning to lock said closure flap in position by pressure thereon to snap said closure beneath said projecting tab and to release said closure from locking position from 5 said tab by pressure on said fixed flap, and sector-shaped side wings formed on the side edges of the closure flap and extending at right-angles to said closure flap toward the interior of said shell and arranged to be shifted into the interior of said shell upon inward movement of said closure flap.

JOHN N. POWELL.
